UMBRELLA COVER CONSTRUCTION AND
TIP THEREFORMax Ornstein and Matthew Ornstein,
New York, N. Y.

Application September 13, 1946, Serial No. 696,638

2 Claims. (Cl. 135—36)

1

This invention relates to umbrella covers, the construction thereof and tips therefor.

Known to us is the art of umbrella construction wherein the cover is anchored to the frame by rib tips sewn to it by hand or machine stitching operations, or which involves tying the cover to the tips by a thread or the like wrapping device. These tips have more frequently been applied with umbrella covers of woven fabric, such as satin, silk or the like woven umbrella covering materials.

With the advent of water resistant plastic film forming materials and the availability of such sheeting, attempts have been made to adapt this sheeting material to the umbrella art, and our endeavors to make these plastic film forming materials or combinations of these foils with cloth available to the umbrella art by merely substituting the tip attaching procedure to covers made of these materials have proven to be unsuccessful.

The inadequacy of the plastic foils or highly coated waterproofed fabrics to resist stitching operations has led to the condemnation of this highly desirable material for use in the umbrella field.

The edging of the covers of plastic foils or highly coated waterproofed fabrics to offset the low tear resisting property of this material further points to the requirement to abandon existing methods of threading, stitching or tying of tips to the umbrella covers of the materials aforementioned.

We have devised, and it is an object of our invention to provide, an umbrella tip which may be effectively affixed to umbrella covers and more particularly to umbrella covers made of plastic films or of foils or highly coated waterproofed fabrics, and which effectively grips the peripheral edge of the cover to withstand the tension involved in stretching the fabric upon the usual umbrella frame when in use.

It is contemplated by our invention, and it is an object thereof to provide, an umbrella tip which may be quickly and effectively attached to the peripheral edge of an umbrella cover and effect substantial economies in labor.

It is contemplated by our invention to provide an umbrella tip which may be quickly and effectively attached to the umbrella cover, at its peripheral edge, whether made of plasticized foils or fabrics or combinations thereof, as distinguished from the laborious practice of sewing or tying such tips with threads to the umbrella cover.

2

In its more specific application, it is an object of our invention to provide an umbrella tip which, when applied to the umbrella cover over the rib end, has the rib cooperate with the rib tip to more effectively grip the peripheral edge of the cover, whereby the tautening of the cover on the umbrella frame serves as an aid to more effectively hold the fabric, rather than to tear against the anchoring influence of the tips with relation to the cover.

Still more particularly, it is an object of our invention to provide an umbrella construction in which the general polygonal contour of the cover is retained, to cooperate with a multi-rib umbrella frame and to anchor the cover by rib tips to the rib ends of the umbrella frame, securing the ornamental benefits of a rib tip without the objectionable tearing or perforating effect due to the heretofore deemed necessity for anchoring 20 tips to the umbrella cover.

Still further it is an object of our invention to provide an umbrella cover and rib tips therefor, the tips being formed to permit speedy and economical anchoring of the same to the peripheral edges of the cover, making possible the use of usual fabrics, as well as plastic foils, films, sheeting or highly coated waterproofed fabrics.

To attain these objects and such further objects as may appear herein or be hereinafter pointed out, we make reference to the accompanying drawing forming a part hereof, in which:

Figure 1 is a fragmentary perspective view showing an umbrella in accordance with our invention;

Figure 2 is a magnified section taken on the line 2—2 of Figure 1;

Figure 3 is a perspective view showing a rib tip in accordance with our invention prior to the attachment thereof;

Figure 4 is a section illustrating a preliminary step of applying a rib tip in accordance with our invention;

Figure 5 is a longitudinal sectional view of a rib tip in accordance with another embodiment of our invention.

Making reference to the drawing, we show an umbrella 10 having the usual frame 11 and cover 11a, in which the ribs 12 are of the type designed to be employed in the umbrella art, intended to have the rib ends thereof generally of cylindrical character at the portion 13, to fit within the socket of the now well-established rib tips.

In accordance with our invention, we provide a rib tip 14, having a generally cylindrical body

15, formed with a socket 16 at one end for receiving the cylindrical end 13 of the ribs 12. In the preferred embodiment of our invention, the body of the rib tip 14 is stamped from metal to form the socket member just described with a flared flange 17, of generally circular contour which, at one end, has an extension 18 merging into an overlying member 19, cooperating with the flange 17 to define a slot 20, and an overlying jaw for the flange 17.

In the embodiment illustrated, the member 19 and the extension 18 may be covered by a facing cap or head 21 comprising some moldable material, such as Celluloid, hard rubber, synthetic resin plastics, which lend themselves readily to ornamentation into different shapes and, to provide different shades or colors. It will be understood, however, that the jaw 19 may be integrally formed with the extension 18 and have a peripheral edge 22 generally conforming to the outline of the flange 17. The extension 18 is selected, in one embodiment of our invention, to provide a deformable section while normally maintaining the jaw 19 in spaced relation to the flange 17.

We will now describe the method of attachment of one embodiment of our invention. In the illustration shown, we have selected an umbrella cover 11a, made of a foil such as Vinylite, a relatively transparent sheeting in general having the appearance of oil-silk, substantially transparent, with more or less uniform distensibility, and which is made by polymerizing various forms of vinyl co-polymers. Other coated waterproof fabrics or the usual umbrella fabrics may also be utilized. It will be understood that foils of requisite toughness such as Pliofilm, a chlorinated rubber derivative, or cellophane, a plasticized regenerated cellulose, are foils which illustrate the general type of homogeneous sheeting which may be employed.

Our invention is particularly applicable to foils or homogeneous films and for this purpose a single or one-piece umbrella cover may be made, cutting the cover into a polygonal shape, the number of sides of the polygon corresponding to the number of ribs in the umbrella frame.

We may, however, employ an umbrella cover in which generally triangular sections are sewn together, the sections corresponding in number to the number of ribs in the umbrella frame, with the sections seamed together, to have each seam overlie the umbrella rib, the peripheral edge of the cover adjacent the rib terminating in a point to which a rib tip is attached.

In accordance with our invention employing a foil such as Vinylite, the completed cover is edged at its peripheral edge 23 with a piping or edging 24, and sewn thereto by stitches 25. This piping may be ordinary ribbon, bias ribbon, braid, tape or edging, which may be applied by a sewing machine having a folder whereby the inwardly directed edges of the tape are simultaneously sewn to the edge of the cover, or which may be attached by any other method.

While we have described the edging as being effected by a sewing operation, it will be understood that the edging may be accomplished by adhesive.

The edging 24 is applied to follow the polygonal contour of the cover, and when so formed, an apex 26 is inserted in the slot 20 of a tip so that the finished surface 27 of the cover lies in substantially the same plane with the upper jaw 19 of the tip. In this position, the extension 18 carrying the jaw member 19 and head or cap 21

is crimped, deformed, or otherwise shaped, forcibly to direct the jaw 19 toward the jaw 17, by a blow or hammer action to anchor the tip to the cover, sandwiching therebetween the edging 24. The periphery of the cover 11a has thereby anchored to it the rib tip 14 through the reinforcement provided by the edging 24.

While the flange 17 and the peripheral edge 22 adequately supply an anchoring engagement upon deformation of the extension 18, it is contemplated by us to augment this binding action. When the cover is applied in position over the umbrella frame, the rib ends 12 are fitted in the cylindrical sockets 16 so that the cylindrical ends 13 project through the socket and engage the edging 24 clamped between the flange 17 and the jaw 19. As the umbrella is put into use, to tension the cover upon the frame, further pressure of the rib end 13 is applied axially through the socket 16 against the edging 24, gripped between the flange 17 and the jaw 19.

Exteriorly, the cover at each of the apices 26 is not only ornamented by the facing cap or head 21 but the facing serves to protect the more fragile cover where it may be abraded in use.

The extension formed by the flange 17 as the umbrella is moved to the open position aids in tensioning the cover fabric over the ribs as well as to pinch the cover peripherally by means of the edging 24, minimizing any cutting or abrading action.

Where the cover is of the usual woven umbrella fabric, the hereinbefore described tensioning action is nonetheless secured.

Our invention in connection with a one-piece cover by the expedient disclosed employing the extension flange 17, serves to give additional tension in using a one-piece foil of the plastic sheeting heretofore described.

By our invention, rib tips may be quickly attached to the periphery of an umbrella cover. The umbrella cover may be held conveniently with relation to the rib tip 14 retained in some crimping or anvil device, where it is then crimped or deformed into cover engaging position. The special needle-aligning accuracy heretofore necessary with rib tips which are sewn in position is completely obviated. The assembly of rib tip and cover may thereby be effected with unusual rapidity.

In another embodiment of our invention, as more particularly illustrated in Figure 5, the rib tip 14a is formed with a body member 15a, having at one side thereof a socket 16a. The socket 16a is closed by a flange 17a, forming one jaw. An extension 18a merges into the jaw 19a, forming the slot 20a. An ornamental facing cap or head 21a may be applied to the jaw 19a as in the prior embodiment.

The flanges 17a and inner surface 21b are formed with serrations 28 having points 29, angularly directed toward the extension 18a. This form of tip may be attached to the umbrella cover as heretofore described in connection with the embodiment illustrated in Figures 1 to 4, disposing the deformed section 18a so that the jaw 19a is brought into cover engaging position, to have the serrations 28 engage the peripheral edge of the cover. These serrations are optional and mere deformation may be employed to grip the fabric. Other means may be used to augment the crimping action without the serrations as will now become apparent.

In this embodiment, the socket 16a engages the umbrella rib end and rides freely thereon. By

having a rib tip with a lateral slot 29a, as described, with the socket thereof freely riding on the rib end, in use in tensioning the cover upon the umbrella frame, the cover equalizes itself on the frame about the rib tip without any twisting or distorting force being applied to the rib tip in its anchoring to the cover.

It is to be understood that by our invention we may employ a one-piece cover or fabric cover, either one of which has its periphery reinforced by selvaging, hemming, or by the use of a binding or tape edging, sewn or cemented to the periphery. The jaw engagement of our tips is particularly effective with the hemmed or round edging which supplement each other.

By our construction not only do we effect substantial economies in labor but the utilization of foils is made commercially practical.

Having thus described our invention and illustrated its use, what we claim as new and desire to secure by Letters Patent is:

1. An umbrella tip having a body, a socket at one end of the body which is generally cylindrically formed for receiving the umbrella rib-end, a flange forming a first jaw at the other end of the body, an extension from said body having a second jaw overlying the flange and forming with said flange a lateral slot, said extension being deformable for bringing said first and second jaws

toward each other into engagement over the umbrella cover, and wherein said flange and second jaw are serrated.

2. An umbrella tip having a body, a socket at one end of the body which is generally cylindrically formed for receiving the umbrella rib-end, a flange forming a first jaw at the other end of the body, an extension from said body having a second jaw overlying the flange and forming with said flange a lateral slot, said extension being deformable for bringing said first and second jaws toward each other into engagement over the umbrella cover, and wherein said extension and second jaw carry a facing cap or head normally axially disaligned and becoming aligned upon deformation bringing the jaws into engagement with the umbrella cover.
